Primary Examiner — Celia A Murphy*Assistant Examiner* — Michael A Pratt(74) Attorney, Agent, or Firm — Grossman, Tucker, Perreault & Pfleger, PLLC(57) CLAIM

The ornamental design for the spectacle case, as shown and described.

DESCRIPTION

FIG. 1 shows a side view of a spectacle case in an unfolded configuration;

FIG. 2 shows another side view of the spectacle case of FIG. 1;

FIG. 3 shows a perspective front view of the spectacle case of FIG. 1;
